ROBERT G. REDMANN, OF BRISTOL, CONNECTICUT

INGOT MOLD CONSTRUCTION

Application filed April 1, 1930. Serial No. 440,842.

My invention relates to improvements in ingot mold construction, pertaining to molds of generally the same form and adapted to the same uses as those that are shown and described in Patents No. 1,730,686 and No. 1,739,769, issued respectively October 8, 1929, and December 17, 1929, being of cast iron and used for casting non-ferrous metal ingots of rectangular form of cross-section, 10 and which comprise mold parts that in the closed position have overlapping faces at the sides, and in which the limit of the closing movement of the parts is determined by opposed flat faces on the two parts that extend 15 for the entire length thereof from the bottom to the top, and the object of my improvement is the provision of improved details for the joint between the two parts, particularly in the faces mentioned, so that 20 the limit mentioned is determined by flat faces of relatively diminutive extent and distributed along the length, the remaining and major portions of said faces being inclined and generally divergent and given 25 unique forms so as to substantially remove and overcome the objectionable results that have heretofore been encountered due to the accumulation of deposit from the liquid brush or swab that is applied to the mold to 30 facilitate removal of the casting.

In the accompanying drawings:—

Figure 1 is a front elevation of my improved ingot mold, with parts of the front part broken away.

Fig. 2 is an edge view of the same.

Fig. 3 is an off-set transverse sectional view through different parts of the joint structure of the two mold parts, being on the line 3—3 of Fig. 1.

In the use of cast iron molds for casting ingots of non-ferrous metals the operator brushes or swabs a liquid solution to the face of the mold to facilitate the removal of the cast bar from the mold. Excess solution runs over at the sides and onto the op-

posed contact faces; as the mold is heated under operating conditions deposit from said liquid burns on and builds up during successive uses in the mold structures in common use; this condition preventing the proper closing of the mold parts; thus a lack of uniformity of castings follows; also, there are extra strains on the mold locking parts, such as the hooks and holding lugs.

My improved ingot mold comprises the front part 10 and the back part 11 hingedly connected by their lower ends and surmounted by the pouring cup 12 that is carried generally by the back part 11 and is positioned above the mold cavity. Holding means at the sides hold the parts closed, such as the hooks 13 on the back 11 that cooperate with lugs 14 on the front 10.

The boundary faces for the mold cavity 15 comprise the flat front face 16 of the front part 10; the flat rear face 17 on the back part 11; and on the two sides are the side faces 18 that, as shown, are provided by the side wall structure 19 of the front part 10. Said side wall structure 19 is projected rearwardly beyond the rear face 17 so that extensions of the side faces 18 overlap opposed faces 20 at the sides of the back part 11 for effecting the seal of the mold cavity 15.

In the usual form of construction the rear end faces of the side wall structures 19 are faced off flat and plain transversely and are opposed to and in face to face contact with similar faces on the back 11.

In the present construction, a brief description would suffice to say that such usual form of construction is retained to a relatively small extent sufficient to positively limit the closing movement of the mold parts, and to this extent only, as by means of suitable contacting lug structures distributed along the length of the mold. Along the other major portions of the length the opposed faces are cut-away or relieved in

some way or other. As shown, the two opposed faces are shaped differently.

Thus the rear face 21, on the back part 11, is simply inclined so as to form with the overlapping face 20 a corner 22 that is in the form of an obtuse angle.

The side wall structure 19 terminates short of the corner 22, being separated therefrom by a short clearance space 23, and 10 the form of the end face thereof comprises a short or narrow face 24 that extends outwardly laterally from the side face 18 in each case. Said narrow face 24 meets the side face to form a right angled corner 25.

15 From the outer end laterally of the narrow face 24 an inclined face 26 completes the end face structure of the side wall structure 19.

The end face structures described serve to ensure a minimum of deposit of foreign 20 matter on the opposed faces of the mold parts; provide means for expelling such material from the cooperating faces; the diminutive clearance spaces 23 preventing obstructions at the opposing corners or the 25 like; provide for relatively free expansion of the sides of the mold parts; and thus provide effective means for generally ensuring uniformity of product. Thus the duty of the clamping devices under conditions of 30 use is relieved.

The limiting lug structures for determining the closing position of the mold parts may be of any proper form and located as desired. Generally the bottom end of the 35 mold cavity would be closed in the usual manner by close fitting faces of the two mold parts, and such faces 28 would provide for positioning of the lower end portions of said mold parts. A set of lugs 27 40 would be provided at the upper end in all cases in the preferred form. Intermediate lugs 29 at the middle as shown in molds of appreciable length and the number and location of such intermediate lugs would be provided to meet certain conditions. Any form 45 of lugs may be used so as to provide opposed flat faces 30 for contacting in the closed position. In machining and finishing the opposed flat faces in the old form of structure 50 a relatively extensive operation is involved. This part of the work is now confined to the diminutive flat faces 30 distributed around the border of the mold.

In some cases the lugs can be provided in 55 the form of loose pieces that can be removed after pouring, after the bar is partly set.

I claim as my invention:—

In ingot mold construction two mating parts enclosing mold cavity side walls of 60 said cavity being integral with one of said parts and extending beyond the said cavity, the other of said parts comprising a body part that fits between said side walls and lateral extensions that are opposed to the 65 end faces of said side walls, said end faces

and lateral extensions comprising relatively diminutive finished cooperating spot-like lug structures that make face to face contact in the closed position of the mold for limiting such closure and all other portions of said end faces and lateral extensions that are generally opposed one to the other being gouged out or cut away so as to prevent contact in such closed position of the mold.
